UNITED STATES PATENT OFFICE.

RUDOLPH F. STEHLIK, OF CHICAGO, ILLINOIS, ASSIGNEE TO AUTOMATIC ELECTRIC INC., OF CHICAGO, ILLINOIS, A CORPORATION OF DELAWARE.

The present invention relates to telephone systems in general, but is concerned more particularly with telephone systems in which arrangements are provided to prevent trunking equipment from being tied up unnecessarily when it becomes apparent that the attempted connection cannot be completed.

As an example of the kind of telephone system above referred to, reference is made to the following U. S. Patents:

1,212,908, Cooley; Jan. 16, 1917. 1,1379,017, Hershey et al., May 24, 1921.

The patents disclose systems in which the connector switch is returned to common use in case the called line is busy, the busy tone being supplied to the calling line from the line switch in one disclosure and from an operator's cord circuit in the other disclosure.

The system to which the present invention is applied differs from the systems of the patents in several ways. In the first place, applicant's system is a multi-office system in which directors are employed for routing the calls to the called offices according to the most economical trunking arrangement, and the means for controlling the apparatus that sends back the busy signal to the calling subscriber when a busy or other abnormal condition is encountered is located in the directors, which are relatively small in number, thus effecting a considerable saving.

An object of the invention is the provision of suitable arrangements whereby the equipment for placing the busy tone on the calling line may be controlled over an inter-office trunk line through an automatic impulse repeater.

Another object of the invention is the production of suitable arrangements whereby the director, which is ordinarily freed immediately upon the transmission of the last digit in the number, is held in the connection momentarily after the last digit is transmitted in order to allow time for the connector to test the called line.

A further object of the invention is to provide suitable circuit arrangements whereby the director is freed and returned to common use, along with the switching equipment, responsive to the encountering of a busy trunk group or other abnormal condition, even though the director has not

reached the stage at which it is normally disconnected and returned to common use.

A further object of the invention is to improve the system by arranging the director to send back dial tone from the time it is seized, until the last digit is dialled, thus reminding the calling man that he has not finished dialling in case he pauses before he is through.

The foregoing objects and features will be better understood, and further features of the invention will manifest themselves, upon a perusal of the following description of the operation of the equipment shown in the accompanying drawings comprising Figs. 1-8.

In the drawings, Figs. 1-3 show the trunking equipment necessary to set up an inter-office connection from a trunk comprising conductors 2-4 to the line of substation B, Fig. 3; Figs. 4-7 show the director that is used in controlling the establishment of a connection and which is associated with the trunk circuit TG, Fig. 1, through the medium of the director selector DS; and Fig. 8 shows a modification of the selector OS, Fig. 1.

In Fig. 1, the trunk comprising conductors 2-4 may be accessible to calling lines through ordinary lineswitches, and, when the trunk is seized, the director selector DS operates to connect up an idle director. The trunk line incoming to the trunk circuit TC is continued through conductors 2'-4' to the office selector OS after the operation of the switching relay 8, which occurs after the connection has been set up to the desired line. The office selector OS has access on one level, as shown, to trunk lines leading to another office and terminating in thousands selectors. For example, the trunk line comprising conductors 84-86 extends to the repeater R, from which a two conductor inter-office trunk line is extended to the second office to the thousands selector TS. It is to be understood that on other levels the office selector OS may have access to thousands selectors, or to other office selectors in the same or another office, depending upon the size of the system and the particular trunking arrangement employed.

Referring now to Figs. 2 and 3, the thousands selector TS has access on its several levels to groups of hundreds selectors, one of which selectors is the hundreds selector

HS. The hundreds selector HS has access to group connectors, one of which connectors is the connector C shown in Fig. 3.

Regarding the mechanical construction of the various switches shown in Figs. 1-3, the selectors and the connector are of the usual vertical and rotary type, having bank contacts arranged in ten horizontal levels, and the director selector DS is assumed to be of the well known rotary type of switch which is used extensively as subscribers' individual lineswitches.

Referring now to the director shown in Figs. 4-7, the portion of the director shown in Fig. 4 includes the sequence switch S, which is used primarily to distribute the incoming series of impulses to the various operating magnets of the registers shown in Figs. 6 and 7. Fig. 4 shows also the sequence switch S' which is used primarily to render effective the various register wipers one after another to control the operation of the sending equipment shown in Fig. 5, and including the sending switch SS.

Fig. 5 shows in addition to the counting switch CS, the usual pick-up and stop relays 404 and 405 which are used to regulate the length of the impulse series in conjunction with the register setting and to perform other auxiliary functions. This drawing shows also the usual release relay 403 and the associated relays 401 and 402 which control the regular switch-through operation and controls the special switch-through operation when an abnormal condition is encountered.

Fig. 6 shows the office register OR and the intermediate distributing frame I. D. F. The office register OR is a two digit switch having a vertical movement and a rotary movement and it registers the office digits of the number. The I. D. F. is provided to enable the control exercised in any given setting of the office register OR to be assigned at will.

Fig. 7 shows the digit registers DR-1-DR-4 which register the thousands, hundreds, tens and units digits, respectively, of the called number, and later control the sending equipment to retransmit these digits.

Assuming now that the trunk line comprising conductors 2-4 is seized by a line switch when a subscriber removes his receiver to extend a connection to the line of substation B, line relay 5 of the trunk circuit TC operates over the calling line when the trunk line is seized. At armature 9, relay 5 closes a circuit for release relay 6, and relay 6 operates and places ground on the release trunk conductor 3 at armature 11 in the usual manner. At armature 12, relay 6 closes a circuit from ground, through the resting contacts and armatures 15 and 21 through switching relay 32 and stepping magnet 31 of the selector DS in series. At

armature 13, relay 6 connects the test wiper 41 of the director selector DS to the junction of relay 32 and stepping magnet 31 through armature 36 and its resting contact and the resting contacts and armatures 22 and 16.

Assuming that the director upon which the wipers of the director selector DS are standing is idle the closing of the test circuit at armature 13 of relay 6 is without result, and switching relay 32 energizes, seizing the director. If, however, the said director is busy, a ground potential is present on the test contact encountered by test wiper 41, and switching relay 32 is short circuited and does not operate. In this case, the ground potential coming in through the test wiper of the switch operates the stepping magnet 31 in its usual buzzer-like manner, advancing the wipers of the switch DS step-by-step until an idle director is reached. Assuming that the director shown in Figs. 4-7 are reached through conductors 43-47 is the first one found to be idle, switching relay 32, being no longer short circuited, energizes when the wipers 38-42 of the switch DS arrive on the bank contacts in which the said conductors terminate. At armature 37, relay 32 prepares the circuit over which the impulses are subsequently transmitted to the director; at armature 36 it opens the test circuit and places ground on test wiper 41; at armature 35 it prepares a circuit for busy relay 7; and at armatures 33 and 34 it connects the conductors 2' and 4' extending to the office selector OS through the wipers 38 and 39 to the outgoing impulse conductors 43 and 44 of the seized director.

When this occurs, line relay 61 of the office selector OS energizes over conductors 43 and 44 and through relay 402, Fig. 5. At armature 71 relay 61 closes a circuit for release relay 62, whereupon relay 62 operates and prepares the switch for operating by grounding the release trunk conductor 3' at armature 72 and by suitably shifting the combined impulse and release circuit at armature 73.

In the director, relay 402 opens at armature 410 a point in the circuit of relay 401, and release relay 403 energizes over the release trunk conductor 46 responsive to the above-mentioned grounding of the test wiper 41 of the director selector DS by relay 32. Upon operating, relay 403 removes ground from the release conductor 319 at armature 411; removes ground from the restoring conductor 316 at armature 412; and at armature 411 and its working contact prepares a circuit for relay 401. Relay 401 is not operated at this time on account of the fact that relay 402 is energized over the control conductors 43 and 44.

Dial tone current from the transformer 230, Fig. 4, now informs the calling sub-

scriber that he may start to dial the number. The lower terminal of the secondary winding being connected to battery through wiper 309 and magnet 502, and the upper terminal is connected to the lower talking conductor over a path that includes the low-capacity condenser 25, Fig. 1.

When the calling subscriber dials the first office digit in the desired number, line relay 10 5 falls back a corresponding number of times, and each time it does so a circuit is closed from ground through the resting contact and armature 10, armature 37 and its working contact, wiper 42 of the director 15 selector DS, the bank contact on which it is standing, conductor 47, left-hand winding of transformer 320, series relay 301, wiper 309 of the sequence switch S, the bank contact on which it is standing, the associated 20 conductor and vertical magnet 502 of the office register OR to battery. By the operation of vertical magnet 502 the wipers of the office register OR are raised step-by-step until they stand opposite the level of bank 25 contacts corresponding to the first office digit in the number.

Series relay 301, Fig. 4, is energized upon the transmission of the first impulse to the vertical magnet of the office register, and, 30 being slow-acting, remains operated throughout the series of impulses. Upon operating, relay 301 closes at armature 303 a circuit for the associated slow-acting relay 302. Relay 302 operates and prepares at armature 304 a circuit which is completed at armature 303 when relay 301 subsequently falls back. This circuit includes magnet 305 of the sequence switch S, which magnet operates when the circuit is closed and advances the wipers 308 and 309 of the sequence switch S one step. The circuit is opened after an instant by the falling back of the slow-acting relay 302.

When the second office digit is dialled, the 45 impulses of current transmitted by line relay 5 of the trunk circuit TC traverse the path above described to wiper 309 of the sequence switch S, but since wiper 309 is now on its second contact, the impulses are delivered 50 over the associated conductor to rotary magnet 501 of the office register OR. By the operation of the rotary magnet, the wipers of the office register OR are rotated step-by-step until they come into engagement 55 with the set of bank contacts corresponding to the second office digit, assumed to be the set shown.

By the above-described action of relays 301 and 302, Fig. 4, the wipers 308 and 309 60 of the sequence switch S are advanced another step at the end of the rotary movement of the office register OR. Wiper 309 shifts the incoming impulse conductor from the rotary magnet of the office register to the operating magnet of the digit register 65

DR-1, Fig. 7, and wiper 308 connects the interrupter 310 to the start conductor 314 extending to the sending equipment shown in Fig. 5. This results in the starting of the sending operation as will be described subsequently.

When the first subscriber digit (the thousands digit) is dialled, the impulses of current are delivered to the operating magnet of the digit register DR-1; the impulses representing the hundreds digit are delivered to the operating magnet of the digit register DR-2; the impulses representing the tens digit are delivered to the operating magnet of the digit register DR-3; and the impulses representing the units digit are delivered to the operating magnet of the digit register DR-4. The result is that the wipers of these registers are set in accordance with the subscriber digits of the desired number, it being understood, of course, that the wipers of the sequence switch S', Fig. 4, are advanced one step at the end of the transmission of each of the above digits.

That being the case, wiper 309 is now stand-

ing on the seventh bank contact, which is dead, and the wipers 308 and 309 remain on their seventh contacts until the connection is released. Also since wiper 307 is on a dead contact, the flow of dial tone current to the calling line stops, reminding the calling subscriber that he has finished dialling.

Returning now to the point at which the interrupter 310, Fig. 4, is connected to the start conductor 314 by the wiper 308 of the sequence switch S at the end of the operation of the office register OR, impulses, under the control of the interrupter 310 are transmitted over conductor 314 and through the resting contact and armature 419 to the stepping magnet 424 of the sending switch SS.

Upon energizing in response to the first of these impulses, magnet 424 operates its associated armature and moves the pawl into engagement with the next step with the wiper-driving ratchet wheel, but does not move the wipers 425 and 426. Also, the sending contacts 423 are opened, but this does not produce any result at this time as the contacts 423 are shunted through armature 418 and its resting contact and armature 413 and its resting contact. Upon the deenergization of magnet 424, the wipers 425 and 426 are advanced one step, and wiper 425 engages a grounded contact, closing a circuit for pick-up relay 404. At armature 413 pick-up relay 404 removes the shunt from around the sending contacts 423 and places a shunt around the series relay 402, and at armature 415 it opens a point in the circuit of relay 401 so as to prevent this relay from operating through armature 410 and its resting contact, responsive to the restoration of the armature of relay 402.

At armature 417, relay 404 opens a point in

the switch-through circuit (to be herein-after described), and at armature 416 it prepares a locking circuit for stop relay 405 and closes a circuit through armature 421 and its resting contact, and over conductor 317 for the stepping magnet 310 of the sequence switch S'. Stepping magnet 310 energizes preparatory to advancing the wipers of the sequence switch when the circuit of the 10 stepping magnet is subsequently opened.

The shunt having been removed from around the sending contacts 423 at armature 413, each subsequent energization of magnet 424 results in an opening of the outgoing 15 control circuit including conductors 43 and 44. It will be noted that stop wiper 426 encounters the first impulse-stop conductor upon the advance of the wipers of the sending switch when magnet 424 falls back after 20 having produced the first interruptions in the outgoing control circuits. The advance of the sending switch and the production of interruptions in the outgoing control circuit continue in any case until a grounded 25 impulse-stop conductor is reached. In this case the single office digit required is the digit 1. Accordingly, the first bank contact 506, Fig. 6, in the set of bank contacts assigned to the 30 instant called office is cross connected on the I. D. F. to the first impulse-stop conductor. That being the case a circuit is closed for stop relay 401 over the first impulse-stop conductor to terminate the office digit 1. The circuit is as follows: From ground by way 35 of the distributing wiper 313 of the sequence switch S', the first associated bank contact, the corresponding conductor, wiper 505 of the office register OR, bank contact 506, the associated I. D. F. jumper, the first impulse- 40 stop conductor, the corresponding contact in the bank of wiper 426, Fig. 5, the said wiper, and stop relay 405 to battery. Upon energizing over this circuit, relay 405 removes at armature 418 the shunt from around the 45 series relay 402, permitting this relay to energize, and replaces the shunt around the sending contact 423; closes another point in the circuit of relay 401 at armature 420; at armature 421 opens the circuit of the stepping magnet of the sequence switch S', Fig. 4, and closes a locking circuit for itself; and at armature 419 opens the interrupter circuit extending to magnet 424 of sending switch SS and closes a restoring circuit 50 for the sending switch by connecting the magnet 424 through the self-interrupting contacts 422 to the restoring wiper 425. Accordingly, the wipers 425 and 426 are advanced to their normal position by the buzzer like action of magnet 424. When the 55 normal position is reached, the circuit for operating magnet 424 and the circuit for maintaining pick-up relay 404 energized is opened by wiper 425. The result is that the pick-up and stop relays fall back one after

the other to start the transmission of the next digit, as will be described subsequently.

Responsive to the opening of its circuit by the stop relay 405, Fig. 5, magnet 319 of the sequence switch S' falls back and advances 70 the wipers 312 and 313 one step. Wiper 313 removes ground from the first wiper of the office register OR and places ground on the second wiper on the office register. Since the office code used for calling the instant 75 called office contains only one digit, the second, third and fourth positions of the sequence switch S' must be skipped automatically without any further code digit being transmitted. This is taken care of, as usual, by jumpering the remaining bank contacts of the office register OR to the skip conductor 318. This being the case, the ground potential is now extended to the second wiper of the office register is extended over the skip conductor 318, by way of the self interrupting contacts 311, Fig. 4, to the stepping magnet 310 of the sequence switch S'. By the usual buzzer like action of the stepping magnet 310, the wipers 312 and 313 are advanced 80 over the second, third and fourth sets of contacts and ground is extended to the wiper of digit register DR-1 preparatory to terminating the thousands digit in accordance with the setting of the register DR-1. 85

When the slow acting pick-up and stop relays 404 and 405, Fig. 5 have fallen back one after the other, relay 405 falling back responsive to the opening of its locking circuit at armature 416 of relay 404, the transmission of the thousands digit takes place in a manner similar to the transmission of the code digit hereinbefore described. In this case, the termination of the digit is determined by the setting of the digit register 100 DR-1 and is effected upon the energization of stop relay 405 over the following circuit:

From ground by way of the distributing wiper 313 of the sequence switch S', the fifth associated bank contact, the corresponding conductor, wiper of the digit register DR-1, the bank contact on which it is standing, the corresponding impulse stop conductor, the corresponding contact in the bank of the sending switch SS, wiper 426, and stop relay 115 405 to battery. The energization of stop relay 405 terminates the digit in the manner described hereinbefore; the sending switch SS is returned to normal; and the sequence switch S' is advanced another step. 120

In a similar manner, the hundreds, tens and units digits are transmitted and are terminated in accordance with the setting of the digit registers DR-2, DR-3 and DR-4, respectively, the wipers of the sequence switch S' being advanced one step in the usual manner at the end of each of the said digits. That being the case, wiper 313 of the sequence switch S' grounds conductor 318 at the end of the transmission of the 130

units digit preparatory to bringing about the switch-through operation in the trunk circuit TC. This switch-through operation is delayed for a slight interval owing to the fact that the switch-through circuit includes the resting contact and armature 417 of the now-energized pick-up relay 404 of the sending switch SS. This is for the purpose of holding up the switch-through operation until the connector switch in use has had time to test the called line and to ascertain whether or not the called line is idle as will be described hereinafter.

Leaving the operation of the director at this point, the operation of the automatic switches in response to the transmission of the code and subscriber digits will now be taken up.

Returning now to the point at which the single code digit 1 is transmitted, line relay 61 of the office selector OS falls back momentarily a single time responsive to the transmission of the code digit 1 and closes at armature 71 a circuit through armature 73 and its working contact and series relay 63 for vertical magnet 67. Vertical magnet 67 responds to this momentary closure of its circuit and raises the wipers 81-83 opposite the first level of bank contacts. The slow acting series relay 68 operates, and, in conjunction with the off-normal contacts 69, which closes upon the first vertical step, completes a circuit from the grounded release trunk conductor 3' for stepping relay 64. Relay 64 operates over this circuit and closes a locking circuit for itself at armature 75, and at armature 76 prepares a circuit for rotary magnet 68.

After a slight interval, the slow acting relay 63 falls back and completes the rotary magnet circuit. Rotary magnet 68 energizes and advances the associated wipers one step onto the first set of bank contacts in the first level, and, near the end of its stroke, opens at its interrupter contacts the circuit of relay 64. Relay 64 falls back and opens the rotary magnet circuit, whereupon the rotary magnet falls back and closes its interrupter contact again.

The operation depends as usual upon whether the trunk line terminating in the first set of bank contacts is busy or idle. If this trunk line is idle, switching relay 65 energizes in series with stepping relay 64, seizing the trunk. If the trunk is busy, however, ground potential is encountered on the test contact thereof by test wiper 82, short circuiting relay 65 and closing a circuit for stepping relay 64. Relay 64 operates and closes at armature 76 the rotary magnet circuit again, whereupon the wipers of the selector are advanced another step.

This alternate operation of stepping relay 64 and magnet 68 continues in this manner until an idle trunk is reached. Assume

this to be the trunk comprising conductors 84-86. When this idle trunk is reached, switching relay 65, being no longer short circuited, operates from ground on the release trunk conductor 3' and through off-normal contacts 69 and the rotary magnet interrupter contacts, and in series with relay 64. Relay 64 does not operate at this time on account of relatively high resistance of relay 65. Upon operating, relay 65 at armature 79 removes ground from armature 71 of line relay 61, opening the circuit of the slow acting release relay 62; opens the test circuit and prepares the holding circuit at armature 78, thereby extending ground to the release trunk conductor of the trunk; and at armatures 77 and 80 disconnects the incoming conductors 2' and 4' from the windings of line relay 61 and extends them by way of wipers 81 and 83, the bank contacts on which they are standing, and conductors 84 and 86, to the windings of line relay 102. Accordingly line relay 102 energizes and closes at armature 107 a circuit for release relay 103, at the same time closing at armature 108 a bridge across the outgoing trunk conductors including relay 105 and the resting contact and armature 112. Responsive to the closure of this bridge, the thousands selector TS in the called office is prepared for operation in the usual manner and relay 105 energizes and opens at armature 114 a point in the circuit of relay 101. Relay 103 upon energizing, prepares at armature 111 a circuit for relay 104; prepares at armature 110 a circuit for relay 101; and at armature 109 places ground on the release trunk conductor 85, thereby closing a holding circuit for the office selector OS before the slow acting release relay 62 has had time to fall back.

When the thousands digit is transmitted by the director, line relay 102 of the repeater R falls back momentarily each time an interruption is produced in the outgoing control circuit of the director. Each time it falls back, line relay 102 opens at armature 108 the bridge across the conductors of the associated interoffice trunk line, resulting in the operation of the thousands selector TS in the usual manner. It will be assumed that the thousands selector TS, upon rotating to find an idle trunk, finds the trunk line extending to the hundreds selector HS idle, and seizes the selector HS.

As a further result of each deenergization of line relay 102, a circuit is closed at armature 107 and through armature 111 and its working contact for relay 104. Relay 104 energizes when its circuit is closed the first time, and, being a slow-acting relay, remains operated throughout the entire digit. At armature 113, relay 104 opens a point in the circuit of relay 101 so as to prevent the operation of this relay at this time, and at

armature 112 it closes the bridge across the conductors of the associated interoffice trunk by a more direct path that excludes relay 105. This is the usual expedient adopted in order to provide a better impulsing circuit.

At the end of the series of impulses, relay 104 falls back and shifts the bridge back to its original path at armature 112, and at armature 113 closes a circuit through relay 101 including armature 114 and its resting contact, and armature 110 and its working contact. Relay 101 does not have time to operate at this time (being slightly slow-to-pull-up) on account of the fact that relay 105 operates again and opens the circuit at armature 104.

When the hundreds digit is transmitted by the director, it is repeated by the repeater R in the foregoing manner to the hundreds selector HS, with the result that the hundreds selector raises its wipers opposite the corresponding level of bank contacts and rotates them in search of an idle trunk line leading to a connector in the desired group.

Assuming that the trunk line leading to the connector C, Fig. 3, and comprising conductors 201-203 is the first one found to be idle, the hundreds selector HS extends the connection to the connector C. That being the case, line relay 209 of the connector C energizes over conductors 201 and 203. At armature 217, relay 209 closes a circuit for release relay 211. Release relay 211 energizes and prepares the operating circuit at armature 220; extends ground to armature 225 of busy relay 214 at armature 219; and at armature 218 places ground on release trunk conductor 202 so as to maintain the preceding selectors operated and so as to furnish current for locking up relays 213 and 216.

When the director transmits the tens digit in the number, this digit is repeated at the repeater R with the result that line relay 209 of the connector C falls back a corresponding number of times. Each time it falls back, line relay 209 closes a circuit for vertical magnet 204, the circuit at the time of its first closure being as follows: From ground by way of armature 217 and its resting contacts, armature 220 and its working contact, contact of off-normal spring 207 and said spring, series relay 212 and vertical magnet 204 to battery. By the operation of vertical magnet 204, the wipers 236-238 are raised step-by-step until they stand opposite the desired level of bank contacts. Series relay 212 energizes upon the first impulse of current and maintains its armature 221 attracted until after the last impulse has been received. Armature 221 maintains the circuit of relay 212 and vertical magnet 204 intact and maintains the rotary-magnet circuit open after the off-normal springs have shifted, as they do upon the first vertical

step. At the end of the vertical movement, relay 212 falls back and shifts the operating conductor from the vertical magnet circuit to the rotary magnet circuit.

When the units is received, the impulses of current generated by line relay 209 are transmitted through armature 221 and its resting contact, resting contact and armature 226, and armature 234 and its resting contact to rotary magnet 208. Rotary magnet 208 responds to these impulses and rotates the wipers 236-238 onto the bank contacts 239-241 of the desired line. Slow acting relay 215 operates responsive to the first rotary impulse and remains operated throughout the rotary movement. At armature 228, relay 215 disconnects test wiper 247 from the upper winding of switching relay 216 and connects it instead to the busy relay 214, and at armature 229 shunts the resting contact and armature 226 so as to maintain its own circuit and that of rotary magnet 208 intact regardless of any energizations of the busy relay 214 that may occur during the rotary movement due to wiper 237 encountering busy test contacts. For a similar reason, armature 230 shunts the resting contact and armature 227.

The operation taking place at the end of the rotary movement of the connector is dependent upon whether the called line is busy or idle. Assuming first that the line is idle, the busy relay 214 remains nonoperated, and the following circuit is closed at armature 228 of relay 215 when the said relay falls back:

From ground by way of the working contact and armature 219, armature 225 and its resting contact, upper winding of relay 216, resting contact and armature 228, test wiper 237, the bank contact on which it is standing, private normal conductor 240, and cutoff relay 242 of the called line to battery. Relays 216 and 242 energize in series with each other, and relay 242 clears the called line of attachments in the usual manner.

In the connector C, relay 216 closes a locking circuit itself at armature 223; by-passes its test winding at armature 232; opens the rotary magnet circuit at armature 234; and at armatures 231 and 235 connects up the line wipers 236 and 238, whereupon ringing current is projected out over the called line, returning to battery through the upper winding of the ring cut-off relay 213.

Returning now to the director, it will be recalled that the switching-through circuit has been prepared by the advance of wiper 313 of the sequence switch S' onto its last bank contact which is connected with conductor 318, and that the switching-through operation is being held up by slow-acting relay 404 to give the connector time to test the called line. It will be recalled also that the circuit of relay 404 is opened upon each

return to normal of the sending switch SS, which return to normal is initiated upon the energization of stop relay 405 at the end of each digit. That being the case, relay 404 falls back at the end of the interval for which it is adjusted and at armature 417 connects the grounded conductor 318 with conductor 47, thereby closing a circuit through wiper 42 of the director selector DS, working contact and armature 37, and armature 10 and its working contact for the switching relay 8. Relay 8 energizes over this circuit and closes at armature 20 a locking circuit for itself from the grounded release trunk conductor 3; opens a further point in the test circuit of the director selector DS at armature 22; at armature 21 opens the circuit of switching relay 32; joins the release trunk conductors 3 and 3' at armature 19; and at armatures 18 and 22 disconnects the incoming conductors 2 and 4 from the windings of relay 5 and extends them to the corresponding conductors 2' and 4' extending to the office selector OS. Relay 32 of the director selector DS now falls back responsive to the opening of its circuit at armature 21 and frees the director, leaving the maintenance of the established connection under the direct control of the calling line.

In the director, relays 402 and 403 fall back when the director is freed, and relay 304 opens at armature 411 a point in the circuit of relay 401 and places ground on release conductor 319, at the same time placing ground on the restoring conductor 316 of the sequence switch S' at armature 412. This latter operation results in the automatic movement of the wipers 312 and 313 of the switch S through the remaining step to their normal position, magnet 310 of the switch S' being operated through wiper 312 and through its self interrupting contacts 311. Responsive to the grounding of conductor 319, release magnet 306 of the sequence switch S energizes through off-normal contacts 307; release magnet 503 of the office register OR energizes through off-normal contacts 504, and the release magnets of the registers shown in Fig. 7 energize through their respective associated off-normal contacts. The result is that all these switches are restored to their normal position in the usual manner. The restoration to normal of the sequence switch S opens at wiper 308 the start circuit so that another operation of the sending switch SS is not started when the slow relay 405 falls back.

When the called subscriber responds to the ringing of his bell by removing his receiver, the transmitter bridge is substituted for the ringer circuit, resulting in the operation of ring cut-off relay 213 of the connector C. At armature 223 relay 213 locks itself to the grounded release trunk conductor 202, and at armatures 222 and 224 it disconnects the wipers 236 and 238 from its own upper winding and from the ringing current lead and completes the talking circuit. Transmitter current now flows from the battery feed impedance 210 to energize the transmitter at the called station. The calling and called subscribers may now converse with each other in the usual manner.

When the conversation is over, the two subscribers replace their receivers, and when the receiver is replaced at the calling substation, line relay 102 of the repeater R, Fig. 2, falls back and opens the bridge across the associated trunk at armature 108, and at armature 107 opens the circuit of release relay 103. Release relay 103 falls back after a slight interval and removes ground at armature 109 from the release trunk conductor 85. There is an incidental operation of relay 104 which prevents the operation of relay 101 after the falling back of relay 105 and prior to the falling back of relay 103.

Responsive to the removal of ground from the release trunk conductor 85, switching relay 65 of the office selector OS and relay 8 of the trunk circuit TC both fall back. Switching relay 65 closes at armature 79 a circuit through armature 71 and its resting contact, armature 73 and its resting contact and off-normal springs 70 for release magnet 66. Accordingly, the selector is restored to its normal position in the usual manner. The calling line switch releases in the usual manner.

In the connector C, Fig. 3, line relay 209 falls back responsive to the opening of its circuit by the repeater R, Fig. 2, and opens the circuit of release relay 211. Release relay 211 falls back after a slight interval and removes ground from conductor 202 at armature 218, at the same time completing the release magnet circuit at armature 220 through the off-normal contacts 206. The operation of release magnet 205 results in the usual release of the connector C. Relays 213 and 216 of the connector fall back responsive to the removal of ground from the release trunk conductor. The intermediate selectors TS and HS both release in a manner similar to that described in connection with the office selector OS, Fig. 1.

It will be assumed now that the line of substation B is busy when called as hereinbefore described. In this case, busy relay 214 is energized when the wipers land on the bank contacts of the called line, and a locking circuit is closed for relay 214 upon the falling back of relay 125. This locking circuit includes armature 225 and its working contact, and the normally closed contacts controlled by armature 228. With relay 214 locked energized, and with relay 215 in a restored condition, the lower winding of relay 209 is disconnected from conductor 203. Accordingly, line relay 209 and relay 130

105 of the repeater R both fall back. Relay 209 opens the circuit of the slow acting release relay 211 and closes a point in the operating circuit, but this circuit is open at 5 armature 226 of busy relay 214.

In the repeater, relay 105 closes at armature 114 a circuit through armature 110 and its working contact for relay 101. Relay 101 energizes over this circuit and opens the 10 circuit of line relay 102 at armature 106, and at armature 115 opens a point in the circuit of relay 104. Line relay 102 of the repeater and relay 402 in the director, Fig. 5, both fall back, and relay 102 opens the circuit of 15 the slow-acting release relay 103 and closes the circuit of relay 104.

In the director, relay 402 closes at armature 410 the circuit of relay 401. Relay 401 at armature 409 places ground on conductor 20 45, thereby closing a circuit through wiper 40 of the director selector DS, and the working contact and armature 35, for relay 7. Relay 7 energizes and locks itself at armature 14, at the same time opening the test 25 and holding circuits of the director selector DS at armatures 16 and 15. Accordingly, relay 32 of the director selector DS falls back and frees the director, which is restored to normal in the usual manner. As a further 30 result of its operation, relay 7 at armature 17 connects the lead coming from the busy signaling transformer 24 to the lower talking conductor 4' through the resting contact and armature 23. The calling subscriber 35 hears the busy signaling tone and is informed thereby that the desired connection cannot be completed for the time being.

In the connector C, Fig. 3, release relay 211 falls back after an interval and closes 40 the release magnet circuit at armature 220, at the same time opening the locking circuit 45 of relay 214 at armature 219. The connector is restored in the usual manner.

In the repeater R, release relay 103 falls 45 back after an interval and opens the circuit of relay 101 at armature 110, ungrounds the release trunk conductor 85 at armature 109, whereupon the office selector OS, Fig. 1, releases.

It will thus be noted that all of the trunking equipment beyond the office selector OS that was involved in the attempt to make connection with the called line is now returned to common use.

It may be pointed out that, if desired, a secondary hunting switch of any suitable type could be inserted between the trunk circuit TC and the office selector OS in the conductors 2', 3' and 4', in which case the 60 office selector OS would be returned to common use at this time by the release of the secondary switch.

When the calling subscriber replaces his receiver, after hearing the busy tone, line 65 relay 5 falls back and opens the circuit of

the slow-acting release relay 6. Relay 6 falls back after an interval and removes ground from the release trunk conductor 3, whereupon relay 7 falls back and the calling line-switch releases.

Assuming now that the office selector OS, having been directed to a certain trunk group by the director shown in Figs. 4-7, rotates its wipers in search of an idle trunk, but is unable to find an idle trunk owing to 75 the fact that all the trunks in the selected level are busy, the wipers 81-83 are driven beyond the last set of bank contacts. In this case the rotary movement stops owing to the fact that no ground potential is encountered 80 by wiper 82 after it leaves the last test contact. Accordingly, relay 65 operates in the hereinbefore described manner to switch the incoming conductors 3' and 4' through to the wipers 81 and 83. When this occurs, 85 relay 402 in the director falls back, followed by the operation of relay 401, which relay closes the above described circuit at armature 409 for relay 7 in the trunk circuit TC. The energization of relay 7 results in 90 the director being freed in the hereinbefore described manner, and in the busy tone being transmitted back to the calling line.

A moment later, release relay 62 falls back and removes ground from conductor 3', 95 whereupon relay 65 falls back and closes the usual release magnet circuit. The switch is then restored to its normal position in the usual manner.

It will be understood of course that substantially the same operation takes place in case an open trunk is found by the office selector OS, if the open trunk is one in which a talking conductor is open. In this case, relay 402, Fig. 5, falls back and closes the 105 circuit of relay 401 when the selector switches through upon finding the open trunk, resulting in the operation of relay 7, Fig. 1, as before described. If the line conductors are both closed, however, and the open trunk is one in which the release trunk conductor (for example, the release trunk conductor 85 of the repeater R) is open, relay 402 does not fall back. When relay 62 falls back, relay 65 of the selector falls back and closes the release magnet circuit, at the same time again connecting up line relay 61. Whether or not the selector releases at this time depends upon the relative adjustment 110 of the release magnet and the line relay. Assuming that the line relay will operate quicker than the release magnet, which is generally the case, the line relay opens the release magnet circuit at armature 71, because the release magnet has had time to operate, and the release and switching relays energize again one after the other, after 115 which the line relay falls back, followed by the falling back of the release relay and the switching relay again. This operation keeps 120

125 130

up until the usual switch-through operation of the director is performed and relay 8 of the trunk circuit TC pulls up and switches the connection through. Then after relay 6 5 has fallen back, the holding up of the calling lineswitch and the continued energization of relay 8 are dependent upon ground supplied over the release trunk conductor 3', and since the ground is intermittently re- 10 moved due to the above described fluttering action of relay 62, relay 8 falls back again and the calling lineswitch and the switch OS release, and the lineswitch seizes the trunk circuit TC anew. The director se- 15 lector operates again as in a new call picks out the same or another director, and the circuits remain in this condition until the calling subscriber either dials again or replaces his receiver.

20 If so desired, the selector OS, Fig. 1 may be replaced by the selector OS', Fig. 8, in which case the operation is the same as before except that the open condition is relayed back over the talking conductors to 25 the director when an open trunk is encountered in which the release trunk conductor only is open, as will be described hereinafter.

A comparison of the selector OS, Fig. 1, 30 and the selector OS', Fig. 8, reveals that the selector OS' is substantially the same as the selector OS with the exception of the addition of armatures 91-95 together with the associated circuit changes. The parts 35 in Fig. 8 that are the same as in Fig. 1 have been given the same reference characters except that the reference characters are primed in Fig. 8. Considering the differences in detail, it will be noted that 40 ground is connected directly to armature 71', Fig. 8, instead of through armature 79' and its resting contact. This is done so as to permit relay 63' to operate again when the selector switches through, and it necessitates 45 that the vertical magnet 67' be cut-off at armature 94 of relay 65, and that armature 79' opens the circuit of the release magnet 66'.

As a result of the above changes, a new 50 operation of relay 63' is secured, but the remainder of operation of the selector is unchanged. When line relay 61' falls back responsive to the operation of relay 65' it closes at armature 71' a circuit through 55 armature 73' for relay 63'. Relay 63' operates and at armature 92 removes the shunt from around armature 91 and its working contact. A moment later relay 62' falls back and removes ground from the circuit 60 of switching relay 65' at armature 72' and at armature 91 disconnects the upper winding of relay 61 from the resting contact of armature 77'. Ordinarily this operation 65 has no immediate effect and the connection remains established. Assuming, however,

that the release trunk conductor of the seized trunk is open, no ground potential is supplied to maintain relay 65' operated after relay 62' falls back, the restoration of relay 62' is followed by the restoration of relay 70 65'. At armatures 77' and 80', the conductors 2' and 4' are again connected to leads extending to windings of line relay 61'. Now, since the upper lead is disconnected at armatures 91 and 92 from the upper winding 75 of relay 61', relay 402, Fig. 5, falls back, resulting in the operation of relay 401 and in the consequent operation of relay 7, Fig. 1, to give the calling subscriber the usual busy tone and to free the director. The release magnet circuit of the selector OS' is closed at armature 79' upon the falling back of relay 65', and the switch is restored to its normal position in the usual manner. A moment later relay 63' falls back and re- 80 connects the upper winding of the line relay to the resting contact of armature 77'. 85

It will be understood of course that the selectors TS and HS, Fig. 2, may be the same as the selector OS', and that the holding 90 ground supplied by armature 93 of relay 63' is of utility in holding up the selector TS momentarily when the selector HS encounters a trunk having an open release trunk conductor. It will be understood further of course, that the encountering of a busy 95 trunk group by the selector TS or by the selector HS produces an effect similar to the encountering of an open trunk, and that this condition is relayed back by the repeater 100 R to the director handling the connection, with the result that the calling subscriber is given the busy signal and the director is freed in the manner hereinbefore described.

105 What is claimed is:

1. In a telephone system, a plurality of lines, a director common to all said lines, automatic switches, means for connecting said director to one of said lines and for operating a train of said automatic switches under the control of said director to set up a connection to a called line, and means in said director controlled over the established connection responsive to a busy condition of 110 the called line for causing said director to be freed.

2. In a telephone system, a plurality of lines, a director common to all said lines, automatic switches, means for connecting 115 said director to one of said lines and for operating a train of said automatic switches under the control of said director to set up a connection to a called line, and means in said director controlled over the established 120 connection responsive to a busy condition of the called line for causing said train of switches to be released.

3. In a telephone system, a plurality of lines, a director common to all said lines, 125

automatic switches, means for connecting said director to one of said lines and for operating a train of said automatic switches under the control of said director to set up 5 a connection to a called line, and means in said director controlled over the established connection responsive to a busy condition of the called line for causing said director to be freed and for causing said train of 10 switches to be released.

4. In a telephone system, a plurality of lines, a director common to all said lines, automatic switches, means for connecting said director to one of said lines and for operating a train of said automatic switches under the control of said director to set up 15 a connection to a called line, and means in said director controlled over the established connection responsive to a busy condition of 20 the called line for causing the calling subscriber to be given a distinctive tone indicative of the busy condition.

5. In a telephone system, a trunk line, subscribers' lines, means for connecting a calling one of said lines to said trunk line, automatic switches, an impulse repeater, means controlled by the calling party for transmitting impulses to said repeater to operate said automatic switches to set up a connection 30 to a called line, means responsive to a busy condition of the called line for placing a special condition on said repeater, and means in said trunk line responsive to said special condition in said repeater for bringing about the release of said automatic switches.

6. In a telephone system, a trunk line, subscribers' lines, means for connecting a calling one of said lines to said trunk line, automatic switches, an impulse repeater, means controlled by the calling party for transmitting impulses to said repeater to operate said automatic switches to set up a connection 40 to a called line, means responsive to a busy condition of the called line for placing a special condition on said repeater, and means in said trunk line responsive to said special condition in said repeater for bringing about the placing of a busy tone on the 50 calling line.

7. In a telephone system, a trunk line, subscribers' lines, means for connecting a calling one of said lines to said trunk line, automatic switches, an impulse repeater, means controlled by the calling party for transmitting impulses to said repeater to operate said automatic switches to set up a connection to a called line, means responsive to a busy condition of the called line for placing a special 55 condition on said repeater, and means in said trunk line responsive to said special condition in said repeater for bringing about the release of said automatic switches and for placing a busy tone on the calling line.

8. In a telephone system, a line, a sender,

automatic switches, means for connecting said sender to said line and for operating a train of said automatic switches under the control of said sender to set up a connection to a called line, a control circuit extending 70 from said sender and closed when the sender is connected to said line, the said control of said automatic switches being effected by interruptions produced in said control circuit by said sender, means for interrupting said control circuit in case an abnormal condition is encountered in the setting up of said connection, and means controlled from said sender responsive to the last named interruption of said control circuit for giving the 75 calling subscriber a busy signal.

9. In a telephone system, a line, a sender, automatic switches, means for connecting said sender to said line and for operating a train of automatic switches under the 85 control of said sender to set up a connection to a called line, a control circuit extending from said sender and closed when the sender is connected to said line, the said control of said automatic switches being effected by interruptions produced in said control circuit by said sender, means for interrupting said control circuit in case an abnormal condition is encountered in the setting up of said connection, means controlled from said sender 90 responsive to the last named interruption of said control circuit for giving the calling subscriber a busy signal, and means for preventing the last named means from responding to the said interruptions produced in 95 said control circuit by the sender.

10. In a telephone system, a plurality of lines, a director common to all said lines, automatic switches, means for connecting said director to one of said lines and for 105 operating a train of said automatic switches under the control of said director to set up a connection to a called line, means for freeing said director after the last automatic switch has been operated, means for delaying the 110 freeing of the director until the last named automatic switch has tested the called line, means in the director controlled from the last named switch if the called line is busy, and means in the line to which the director is 115 connected and responsive to said means in the director for placing a busy tone to the last named line and for releasing said switches.

11. In a telephone system, an automatic 120 switch having access to trunk lines, talking conductors incoming to said switch, means for producing a current flow in said conductors and for interrupting said flow to operate said switch, and means in said switch for 125 producing a substantial interruption in said current flow responsive to an open condition of the test conductor of any seized trunk.

12. In a telephone system, means including two automatic switches in serial relation for 130

- setting up a connection to a trunk line accessible to the second switch responsive to current-flow interruptions in the talking conductors incoming to said switches, means 5 in the second switch for holding the first switch operated before the trunk line is seized, a holding conductor in the trunk line for holding both switches operated after the trunk line is seized, and means in said switch 10 for interrupting the current flow in the talking conductors incoming to the second switch responsive to an open condition of the holding conductor of said trunk line and for holding the first switch operated at the same 15 time so that the current flow is also interrupted in the conductors incoming to the first switch.
13. In a telephone system, automatic switches for setting up connections, a director for controlling said switches, means in said director for performing a characteristic switching operation in case a switch which is being controlled selects a trunk line having an open talking conductor, and 20 means in one of said switches responsive to the selection of a trunk line having an open test conductor for producing an artificial open circuit condition in the trunk line incoming to such switch in order to operate 25 the said switching means in said director.
14. In a telephone system in which connections are set up responsive to successive operations of a calling device, means for giving the calling party a distinctive signal 30 informing him that he may now operate his calling device and for giving him said signal again in case he stops operating his calling device before he has turned it a sufficient number of times.
15. In a telephone system in which connections are set up responsive to successive operations of a calling device, means for giving the calling subscriber a continuous signal until he has operated his calling device 35 a sufficient number of times.
16. In a telephone system in which connections are set up responsive to successive operations of a calling device, means for giving the calling subscriber a signal and for removing it responsive to the last operation of the calling device.
17. In a telephone system, means including a register sender for operating a train of automatic switches to set up a connection 40 to a desired line, and means in said register sender controlled through said train of switches responsive to a busy condition of the called line for causing a busy tone to be placed on the calling line.
18. In a telephone system, means including a register sender for operating a train of automatic switches to set up a connection 45 to a desired line, means in said register sender controlled through said train of switches responsive to a busy condition of the called line, and means controlled thereby for informing the calling party over the calling line of the busy condition of the called line.
19. In a telephone system, means including a register sender for operating a train of automatic switches to set up a connection to a desired line, and means in said register sender controlled through said train of switches responsive to a busy condition of the called line for causing said train of automatic switches to be released.
20. In a telephone system, means including a register sender for operating a train of automatic switches to set up a connection to a desired line, means in said register sender controlled through said train of switches responsive to a busy condition of the called line and means controlled thereby for releasing said train of automatic switches and for informing the calling party over the calling line of the busy condition of the called line.
21. In a telephone system wherein connections are set up from a calling line to a called line through a trunk line by means of a train of automatic switches, a controlling device common to said trunk line and to a plurality of similar trunk lines and arranged to be temporarily connected with any one of said trunk lines, and means in said controlling device responsive to a busy condition of a desired line for placing a busy condition on the calling line.
22. In a telephone system wherein connections are set up from a calling line to a called line through a trunk line by means of a train of automatic switches, a controlling device common to said trunk line and to a plurality of similar trunk lines and arranged to be temporarily connected with any one of said trunk lines, and means in said common controlling device responsive to a busy condition of a desired line for causing the release of said train of automatic switches.
23. In a telephone system wherein connections are set up from a calling line to a called line through a trunk line by means of a train of automatic switches, a controlling device common to said trunk line and to a plurality of similar trunk lines and arranged to be temporarily connected with any one of said trunk lines, and means in said common controlling device responsive to a busy condition of a desired line, and means controlled thereby for releasing said train of automatic switches, and for causing a busy tone to be applied to the calling line.
24. In a telephone system wherein connections from calling lines are extended by automatic switching apparatus to trunk lines and are extended from such trunk lines to called lines by way of other automatic

switching apparatus, means including busy signalling apparatus individual to each of said trunk lines for informing the calling party of a busy condition, a controlling device common to all of said trunk lines and arranged to be temporarily connected to any one of them, and means in said controlling device responsive to a busy condition of a line to which a connection is attempted over a trunk line to which it is temporarily connected for causing the busy signalling means individual to such trunk line to become effective.

25. In a telephone system wherein connections from calling lines are extended by automatic switching apparatus to trunk lines and are extended from such trunk lines to called lines by way of other automatic switching apparatus, means including busy signalling apparatus individual to each of said trunk lines for informing the calling party of a busy condition, a controlling device common to all of said trunk lines and arranged to be temporarily connected to any one of them, means in said controlling device responsive to a busy condition of a line to which a connection is attempted over a trunk line to which it is temporarily connected for breaking down the attempted connection.

26. In a telephone system, a repeater arranged to control the operation of automatic switches over an inter-office trunk line, said repeater having a pair of incoming talking conductors, a source of transmitter supply 35 current connected to said talking conductors through a repeating relay, a pair of outgoing talking conductors having a relay connected in a bridge thereof, contacts on said repeating relay included in said bridge, the 40 arrangement being such that when the repeater is included in a connection the repeating relay is energized over the incoming conductor and the bridge across the outgoing conductors is closed by the contacts of 45 the repeating relay so that the relay connected in the bridge of the outgoing conductors is operated, circuit connections controlled by the relay in said bridge in case the current supply to the outgoing talking 50 conductors is interrupted outside of said repeater for interrupting current flow over the incoming conductors, and means for preventing the last named interruption when the current flow through said bridge is interrupted by the impulse relay during the 55 normal functioning of the repeater.

In witness whereof, I hereunto subscribe my name this 1st day of June, A. D., 1926.

RUDOLPH F. STEHLIK.
